SPEED RESPONSIVE APPARATUS

Application filed November 24, 1931. Serial No. 577,057.

Our invention relates to speed responsive apparatus, and particularly to improvements in speed responsive apparatus of the type described and claimed in an application for 5 Letters Patent of the United States, Serial No. 551,967, filed by Frank H. Nicholson, on July 20, 1931.

Speed responsive apparatus embodying our invention is particularly suitable for, although in no way limited to, use for controlling circuits in conjunction with speed control systems for railroads.

We will describe three forms of apparatus embodying our invention, and will then point 15 out the novel features thereof in claims.

In the accompanying drawings, Fig. 1 is a view, partly in section, partly in side elevation, and partly diagrammatic, illustrating one form of apparatus embodying our invention. Figs. 2, 3, 4 and 5 are diagrams, showing graphically, the operating characteristics of a portion of the apparatus illustrated in Fig. 1. Fig. 6 is a view, similar to Fig. 1, showing a modified form of the apparatus 20 illustrated in Fig. 1, and also embodying our invention. Fig. 7 is a diagram, showing graphically, the operating characteristics of a portion of the apparatus illustrated in Fig. 6. Fig. 8 is a view, partly in side 25 elevation, partly in section, and partly diagrammatic, illustrating another form of apparatus embodying our invention. Fig. 9 is a sectional view taken on the line IX-IX of Fig. 8. Fig. 10 is a view showing a modified 30 form of a portion of the apparatus illustrated in Figs. 8, and 9, and also embodying our invention, and Fig. 11 is a sectional view taken on the line XI-XI of Fig. 10.

Similar reference characters refer to similar parts in each of the several views.

Referring first to Fig. 1, speed responsive apparatus embodying our invention embraces suitable speed responsive circuit interrupting means, designated as a whole by the reference character M, and here shown as comprising a rocker 1 and an inertia member 2 which cooperates with the rocker 1. The rocker 1 is mounted to oscillate about a suitable shaft indicated at 3 in the drawings, and 45 is intended to be operatively connected with

any body or device whose linear or angular speed it is desired to measure, in such manner that the frequency of oscillation of the rocker will be proportional at all times to the speed of the body or device. In the embodiment illustrated, the rocker 1 is operatively connected with the axle 6 and wheel 7 of a car or locomotive, not shown in the drawing, by means of a connecting rod 4. The connecting rod 4 is pivoted at one end on a pin 1^b carried by an extension 1^a on the rocker 1, and at the other end on a crank pin 5 which is eccentric to the axle 6 and wheel 7. It will be apparent, therefore, that when the wheel 7 is rotated, the rocker 1 will be 55 oscillated at a frequency which is directly proportional to the speed of the wheel, the frequency of the rocker being increased as the speed of the wheel increases, and decreased as the speed of the wheel decreases. It follows, therefore, that the frequency of oscillation of the rocker will increase or decrease as the linear speed of the locomotive or car of which the wheel 7 forms a part increases or 60 decreases. It should be distinctly understood, however, that the particular arrangement shown is utilized merely for the convenience in describing our invention, and not by way of limitation.

The inertia member 1 is pivotally mounted 65 on a shaft 9 carried by the rocker 1 and, in the form here shown, comprises two spaced weights 2^a and 2^b connected by integral webs 2^c and 2^d with a sleeve portion 2¹ which receives the shaft 9. Interposed between an arm 11 secured to the weight 2^b and an adjustable spring support 12 screwed through the web 1^c of the rocker 1, is a coil spring 13 which biases the inertia member 2 to a position in which a contact member 14 secured to 70 the weight 2^a engages a contact member 15 attached to, but insulated from, the web 1^c of the rocker 1. The spring support 12 is locked in an adjusted position by means of a lock nut 16.

The apparatus also includes a reactance X and an electroresponsive indicating device, here shown as a relay R. The reactance X and relay R are connected in series in a circuit 75 which passes from terminal B, of a suitable 80

source of current not shown in the drawing, through rocker 2, contact 14—15, reactance X, and the winding of relay R to the other terminal O of the source. Connected in 5 multiple with reactance X and relay R in the circuit just traced is an asymmetric unit A which is so disposed that it will offer its highest resistance to current which tends to flow through the branch path including this 10 unit from terminal B to terminal O of the source. Relay R is preferably made slow-acting for reasons which will appear as the 15 description proceeds.

The operation, as a whole, of the apparatus 20 thus far described is as follows: As previously pointed out, when the wheel 7 is rotated, the rocker 1 is oscillated at a frequency which increases as the speed of rotation of the wheel 7 increases. At all frequencies of oscillation of the rocker, the motion of the rocker is substantially simple harmonic motion, and it will be apparent, therefore, that when the rocker is oscillating, it causes an accelerating force to be exerted 25 on the inertia member 2 which varies according to a sine curve. This accelerating force is always in opposition to the force causing the displacement of the rocker from the position in which it is shown in Fig. 1, and it will be 30 readily understood that during that portion of each oscillation in which the rocker is being rotated in a clockwise direction from the position shown in Fig. 1, this accelerating force is transmitted to the rocker through 35 the spring 13. That is to say, during that portion of each oscillation in which the rocker 1 is being rotated from the position shown in Fig. 1 in a clockwise direction, the accelerating force of the inertia member is opposed by 40 the force of the spring 13. The magnitude of the accelerating force acting on the inertia member increases with increases in the frequency of oscillation of the rocker according to the square of the frequency, and it will be 45 seen, therefore, that as long as the frequency of oscillation of the rocker remains below some frequency which we shall term the "critical" frequency, and which depends upon the proportioning of the parts, the accelerating force acting on the inertia member will 50 always be less than the opposing force of spring 13, and under these conditions, contact 14—15 will remain continuously closed. As soon, however, as the frequency of oscillation 55 of the rocker increases beyond this critical frequency, a condition will be reached during some portion of each oscillation in which the accelerating force acting on the inertia member is greater than the opposing 60 force on the spring, and when this happens, the spring will no longer be able to hold the inertia member against the rocker, with the result that the spring will become compressed and permit contact 14—15 to open. When the 65 contact has once opened, the motion of the in-

ertia member is governed by the inertia of the inertia member and by the opposing force of the spring. The opposing force of the spring depends, among other things, upon the relative position of the inertia member with respect to the rocker, and it will be clear, therefore, that after the contact has once opened, the inertia member will continue to move in the direction to increase the contact opening for a time, but will soon come to rest, and will then move with increasing velocity in a direction to again close the contact. Considering the motion of the rocker during this time, it is evident that its acceleration increases to a negative maximum as it comes to rest at the end of its stroke in the clockwise direction of rotation, and then decreases as it moves in the opposite direction, becoming zero at mid stroke. At some point after the rocker has reversed the direction of its rotation from clockwise to counter-clockwise, the acceleration of the rocker will be less than that which caused the contact to open. When this happens, the rocker and inertia member will each be moving in the counter-clockwise direction, and the inertia member will be accelerating at a rapidly increasing rate. It is evident, therefore, that the contact will again become closed during each oscillation at some later point in the cycle than the point at which it opened. Since the acceleration of the inertia member varies as the square of the frequency of oscillation of the rocker, it follows that the length of the open time of contact 14—15 during each oscillation will rapidly increase, and the length of the closed time will rapidly decrease, with slight increases in the frequency of oscillation of the rocker beyond the critical frequency. It should be pointed out, that, since for a given proportioning of the parts, the weight of the inertia member and the relative locations of the shafts 9 and 3 are fixed, the critical frequency at which contact 14—15 first opens, may be varied by varying the adjustment of the spring 13.

As was previously pointed out, contact 14—15 is included in the circuit for reactance X and relay R, and it follows that when contact 14—15 is closed, this circuit will be closed, and current will therefore be supplied to the winding of relay R. It will be readily understood, however, that due to the inductance of this circuit the current in the winding of the relay will not build up to its Ohm's law value immediately upon the closing of this contact, but will follow a time constant curve similar to the curve 18 shown in Fig. 3. Likewise when contact 14—15 is opened, the circuit for reactance X and relay R will become interrupted, and the supply of current to the relay will therefore be cut off. At the instant the supply of current to the relay is cut off, the current in the winding of the relay will start to decrease, but due to the

energy stored in this winding and in reactance X , a circulating current will be set up in the closed circuit including the winding of the relay, reactance X , and asymmetric

unit A , and this circulating current will delay the decay of current in the winding of the relay in a manner which is indicated graphically by the time constant curve 17 shown in Fig. 2. It will be seen, therefore, that if contact 14-15 is alternately opened and closed at a fixed rate, as is normally the case when the rocker is being oscillated at any constant frequency above the critical frequency, the current in the winding of the relay will first decrease during each oscillation along some portion of the curve 17 to some value which depends upon the initial value of the current in the winding of the relay at the instant contact 14-15 became opened, and upon the length of time the contact remains opened, and will then increase along some portion of the curve 18 to the same value which it had when the contact last became opened. This growth and decay of the current in the winding of relay R at one particular frequency of oscillation of the rocker above the critical frequency is indicated graphically by the curve 20 shown in Fig. 4. Referring to this figure, the line $b-c$ of the curve 20 represents the decrease in current in the relay winding during one oscillation, and the line $c-b^1$ indicates the increase in current during the same oscillation. During the next succeeding oscillation, the decrease in current is represented by the line b^1-c^1 , and the increase in current by the line c^1-b^2 , etc. It will be seen, therefore, that at one particular frequency of oscillation of the rocker above the critical frequency, the winding of the relay will be supplied with a periodically varying current, the average value of which is indicated by the line 21 in Fig. 4.

As described hereinbefore, the open time of contact 14-15 increases, and the closed time decreases, as the frequency of oscillation of the rocker increases beyond the critical frequency. It will be readily understood, therefore, that at the higher frequencies of oscillation of the rocker, the current has less time to build up, and consequently does not build up to such a high value as it does at the lower frequencies. Also, since the open time of the contact is greater, the current decays to a lower value. The periodically varying current which is supplied to the relay winding when the rocker is oscillating at a frequency which is somewhat higher than the frequency of oscillation corresponding to that for the curve 20, is indicated by the curve 22 shown in Fig. 4, and the average value of the current which is supplied to the relay winding under these conditions is indicated by the curve 23. From a comparison of the curves 20 and 22, it will be seen that

as the frequency of oscillation of the rocker increases beyond the critical frequency, the average current in the relay winding decreases.

Referring now to Fig. 5, the curve 24 here shown is a typical curve indicating the manner in which the average value of the current which is supplied to the relay winding varies with variations in the frequency of oscillation of the rocker 1 for one particular proportioning of the parts. From an inspection of this curve it will be seen that, at all frequencies below the critical frequency, the average value of the current in the relay winding is substantially constant. The reason for this is that, since contact 14-15 remains closed at all frequencies below the critical frequency, the current in the winding of the relay builds up to, and remains at, its Ohm's law value. As soon as the frequency of oscillation of the rocker passes the critical frequency, however, so that contact 14-15 starts to periodically open and close, the average value of the current in the relay winding starts to decrease, and as the frequency of oscillation of the rocker continues to increase, the current decreases more and more rapidly until, at a narrow band of frequencies just a little above the critical frequency, the decrease is very rapid. As the frequency further increases beyond this narrow band of frequencies, the decrease in current becomes less marked until a frequency is finally reached at which the rate at which the contact 14-15 interrupts the circuit for the reactance X and relay R becomes so high that substantially no further decrease in current takes place.

As was pointed out hereinbefore, relay R is a slow-acting relay, and it will be readily understood, therefore, that by properly proportioning its parts, this relay may be made to respond to the average value of the current supplied to its winding, and not to the instantaneous value. It will be seen, therefore, that by constructing this relay to have pick-up and release values which fall on some portion of the curve 24, the relay will be picked up at all frequencies of oscillation of the rocker below the frequency corresponding to the pick-up value, and will be released at all frequencies of oscillation of the rocker above the frequency corresponding to the release value. For example, if the relay is provided with the pick-up value indicated by the line 25 in Fig. 4, and with the release value indicated by the line 26 in Fig. 4, the relay will be picked up at all frequencies of oscillation of the rocker below that indicated by the line 28, and will be released at all frequencies of oscillation of the rocker above that indicated by the line 27. It will be readily understood, of course, that as the frequency of oscillation of the rocker is increased from some value below the critical frequency to some value be-

yond the frequency at which the relay releases, the relay will remain picked up until the frequency at which the relay releases is reached, and that as the frequency of oscillation of the rocker is decreased from some value which is higher than the frequency at which the relay releases to some frequency which is below the frequency at which the relay picks up, the relay will remain released until the frequency at which the relay picks up is passed. It will be remembered that the critical frequency of the rocker depends upon the proportioning of the parts, and that for a given proportioning of the parts, this frequency may be varied by adjusting the position of the spring support 12 to vary the biasing force exerted by the spring 13. It will be seen, therefore, that by properly selecting the electrical and mechanical elements of the apparatus, and by properly adjusting the biasing force of the spring 13, relay R may be made to pick up and release its armature at any desired frequency of oscillation of the rocker, and hence, at any desired linear speed of the car or locomotive with which the rocker is operatively connected. It will also be seen that by adjusting the pick-up and release values of the relay R to such values that they fall on the steep portion 30 of the curve 24 as indicated by the lines 25 and 26, the relay may be made to pick up and release its armature at frequencies which differ in magnitude by only a small amount. This is particularly desirable when the relay is to be utilized for controlling circuits in connection with speed control systems for railroads.

When relay R is picked up, its front contact 19-19^a is of course closed, and when the relay is released, its back contact 19-19^b is closed. The contacts of the relay may be utilized to control the circuits for any suitable electro-responsive device or devices in such manner that the device or devices will occupy one condition when the relay is energized and another condition when the relay is de-energized. For example, when the apparatus is operatively connected with some part of the running gear of a car or locomotive, as is the case in the embodiment illustrated, so that the frequency of oscillation of the rocker 1 varies with the linear speed of the car or locomotive, relay R may be utilized to control a speed governing device for the car or locomotive. As here shown, relay R controls a brake controlling magnet E which applies the brakes on the car or locomotive when this magnet becomes deenergized. The circuit for magnet E is carried over front contact 19-19^a of relay R. It will be apparent, therefore, from the foregoing, that as long as the speed of the car or locomotive is below some predetermined speed, magnet E will be energized, but that if the speed of the car or locomotive increases beyond this speed, mag-

net E will become deenergized, thus enforcing a low speed limit on the car or locomotive. It should be definitely understood, however, that apparatus embodying our invention is in no way limited to this particular use.

Referring now to Fig. 6, the apparatus here shown is similar to that shown in Fig. 1 with the exception that the inertia member 2 of the circuit interrupting means, which circuit interrupting means is here designated generally by the reference character M¹, instead of being biased by means of the spring 13 to the position in which the contact 14-15 is closed as shown in Fig. 1, is biased by means of a spring 58 to the position in which the contact 14-15 is open. The spring 58 is secured at one end to the arm 11, and at the other end to an adjustable eyebolt 59 which is screwed through the web 1^a of the rocker 1. The eyebolt 59 is locked in place by means of a nut 60. An adjustable stop 61 limits the amount of opening of the contact 14-15.

With the apparatus constructed as shown in Fig. 6, when the rocker 1 is oscillated, the inertia of the inertia member 2 will aid the spring 58 in holding contact 14-15 open during a portion of each oscillation but will tend to stretch the spring, and hence to close the contact 14-15, during another portion of each oscillation as will be readily understood from the foregoing description of Fig. 1. It will be apparent, therefore, that as long as the frequency of oscillation of the rocker remains below some critical frequency which depends upon the proportioning of the parts and the adjustment of the spring 58, contact 14-15 will constantly remain open, but that, as soon as the frequency of oscillation of the rocker becomes greater than this critical frequency, contact 14-15 will start to alternately open and close, the length of the closed time increasing, and the length of the open time decreasing, as the frequency of oscillation of the rocker increases beyond the critical frequency. As previously pointed out in connection with Fig. 1, when contact 14-15 is open, the circuit for reactance X and relay R is interrupted, and the current in the winding of the relay decays. When this contact is closed, however, the circuit for reactance X and relay R is then closed, and the current in the relay winding builds up. It follows, therefore, that as long as the frequency of oscillation of the rocker is below the critical frequency, relay R will constantly remain deenergized. As soon, however, as the frequency of oscillation of the rocker becomes greater than the critical frequency so that contact 14-15 becomes alternately opened and closed, the winding of the relay will be supplied with a periodically varying current, the average value of which will increase as the frequency of oscillation of the

rocker increases. The manner in which this increase takes place for one proportioning of the parts is indicated by the curve 62, shown in Fig. 7. Referring to this figure, it will be observed that as soon as the critical frequency of the rocker is passed, the average value of the current supplied to the relay winding first increases gradually and then more and more rapidly until a narrow band of frequencies is reached between which the increase is very rapid. As the frequency increases beyond this narrow band of frequencies, the increase in current becomes less rapid until a frequency is finally reached where very little further increase in current takes place, and the average value of the current for further increases in the frequency of oscillation of the rocker then remains substantially constant. Since relay R is constructed to respond to the average value of the current supplied to its winding, it follows that by providing the relay with pick-up and release values which fall on the curve 62, the relay will be released at all frequencies of oscillations of the rocker below the frequency corresponding to its release value, and will be picked up at all frequencies above that corresponding to its pick-up value.

When the parts are arranged as shown in Fig. 6, relay R may be utilized to control any suitable device in any desired manner.

Referring now to Figs. 8 and 9, in the modified form of our invention here shown, the circuit interrupting means is designated as a whole by the reference character M², and is enclosed in a suitable casing C, which may, for example, be secured to some stationary part 31 of the car or locomotive in such manner that its position with respect to the axle 6 of the car will remain fixed. One side wall 33 of the casing C is formed with a bearing 30, and the opposite side wall 34 thereof is provided with an opening 35. The opening 35 is closed by a suitable cover plate 36 having a bearing 29 formed therein which is in axial alignment with the bearing 30. A horizontally extending shaft 38, to which a rocker 1^f is rigidly secured, is journaled in the bearings 29 and 30, and the right-hand end 38a thereof extends through the casing and is provided with a crank 37. The free end of the crank 37 is pivotally connected with the upper end of the connecting rod 4 previously described in connection with Fig. 1. It will be seen, therefore, that when wheel 7 is rotated, the rocker 1^f will be oscillated at a frequency which increases as the speed of the wheel, and hence as the linear speed of the car, increases. For reasons which will appear hereinafter, the right-hand end 38a of the rocker 1^f is made tubular, and extending from the interior of the casing through this tubular portion into the opening therein are a plurality of holes 39, as clearly shown in Fig. 8.

Pivots mounted on the shaft 38 between bosses 38b and 40 formed on the rocker 1 are a plurality of inertia members 2^e, 2^f, and 2^g. Each of these inertia members is similar to the inertia member 2 shown in Fig. 1, and each is biased, by means of an associated adjustably spring 13^e, 13^f, or 13^g to the position in which a contact finger 14^e, 14^f, or 14^g carried thereby engages a fixed contact member 15^e, 15^f or 15^g, carried by the rocker, as will readily be understood from an inspection of Figs. 8 and 9. External electrical connections to all of the contact fingers 14 is made by means of a flexible conductor 41 which extends through the opening in the tubular portion 38a of the rocker 1^f and through one of the holes 39, and which is fastened to each inertia member by means of a suitable screw 45. External electrical connections to the fixed contact members 15^e, 15^f and 15^g are similarly made by means of flexible conductors 42, 43 and 44, respectively, each of which extends through a different hole 39 into the opening 38a in the tubular end of the rocker 1^f and is soldered or otherwise fastened at its inner end to the associated fixed contact member.

The contact 14^e—15^e controls the supply of current to an electrical circuit which passes from terminal B of the source through flexible conductor 41, inertia member 2^e, contact 14^e—15^e, flexible conductor 42, and an asymmetric unit A^e connected in multiple with a reactance X^e and the winding of a relay R^e in series, to terminal O of the source. The reactance X^e, relay R^e and asymmetric unit A^e are similar in all respects to the reactance X, relay R and asymmetric unit A previously described in connection with Fig. 1. The contacts 14^f—15^f and 14^g—15^g control the supply of current to similar circuits which will be apparent from the drawings without describing them in detail.

The operation of the apparatus shown in Figs. 8 and 9, in so far as the elements associated with each inertia member is concerned, is substantially the same as that previously described in connection with Fig. 1, and will be readily understood without further description. It should be pointed out, however, that by properly adjusting the springs 13 associated with the different inertia members, the contacts 14^e—15^e, 14^f—15^f and 14^g—15^g may be made to first open at different frequencies of oscillation of the rocker 1^f, and under these conditions, the relays R^e, R^f and R^g will operate at different speeds of the car or locomotive, thus enabling a plurality of different speed limits to be enforced on the car or locomotive.

Referring now to Figs. 10 and 11, we have here shown a modified form of the circuit interrupting apparatus illustrated in Figs. 8 and 9. As here shown, the rocker 1^f cooperates with three inertia members 2^h, 2^j and 2^k.

and 2^k , each of which is in the form of a substantially rectangular block. Each of the inertia members is pivotally mounted on the shaft 38, and has secured to its face which is nearest the web of the rocker 1^f a leaf spring 46^h , 46^i or 46^k . The upper ends of the leaf springs 46^h , 46^i and 46^k are provided with contact tips 47^h , 47^i and 47^k , respectively, which cooperate with similar contact tips 48 , only the tip 48 which cooperates with the contact tip 47^k being visible in the drawings. The contact tips 48 are each fastened to the upper ends of a fixed contact member 49 , and the contact members 49 , in turn, are fastened to, but insulated from the rocker 1^f . The lower ends of the leaf springs 46^h , 46^i and 46^k cooperate with suitable adjusting members 50^h , 50^i and 50^k in such manner that the inertia members are constantly biased by the springs to the positions in which the contacts 47^h — 48 , 47^i — 48 and 47^k — 48 are closed. It will be apparent, therefore, that the leaf springs 46 serve both as contact fingers and as biasing means. The adjusting members 50^h , 50^i and 50^k are screwed through threaded holes in the web of the rocker 1^f , and in the form here shown, each adjusting member comprises a metal plug 50 provided at its inner end with an insulating insert 56 which insulates the adjacent leaf spring from the rocker. Each adjusting member is maintained in its adjusted position by means of a lock washer 52 having a threaded hole 53 which receives the member (see Fig. 11) and an integral lug 55 through which a screw 54 which is screwed into the rocker 1^f passes. To lock an adjusting member in an adjusted position, the associated washer 52 is screwed onto the adjusting member to a position in which it is spaced a slight distance from the rocker, and the screw 54 is then tightened, thus binding the threads of the adjusting member, and hence preventing it from turning. It will be noted from an inspection of Fig. 10 that the lower portion of the inertia member 2^k adjacent the spring 46^k is curved as indicated at 57 in the drawings. This curvature is so shaped and arranged that the free end of the spring 46^k becomes shorter and rapidly increases in stiffness as soon as the contact 14 — 15 has opened. This feature is important particularly when a comparatively heavy inertia member must be adjusted to open the contacts at a comparatively low speed and at the same time be capable of properly following the oscillations of the rocker at higher rates of speed without an excess opening of the contacts. The curvature of the lower portion of the inertia member also tends to decrease wear between the parts. The other inertia members are likewise curved in a similar manner. In the structure shown, it is intended that the contacts 47^h — 48 , 47^i — 48 and 47^k — 48 shall first open at different frequencies of oscillation

of the rockers, and in order to facilitate this operation, the mass of the inertia member which operates the contact which is intended to first open at the highest frequencies of oscillation of the rocker is made somewhat less than the mass of the inertia member which operates the contact which is intended to open at the next lower frequency of oscillation of the rocker, etc., as will be clearly apparent from an inspection of Fig. 10.

With the circuit interrupting means constructed as shown in Fig. 10 when the rocker 1^f is operated, each inertia member cooperates with the rocker to control the associated contact in substantially the same manner as the rocker 2 shown in Fig. 1 cooperates with the rocker 1 to control the contact 14 — 15 . The parts are so proportioned, however, and the springs 50 are so adjusted that the contact 47^h — 48 will first become periodically opened and closed at a relatively low frequency of oscillation of the rocker, the contact 47^i — 48 at a somewhat higher frequency of oscillation of the rocker, and the contact 47^k — 48 at a still higher frequency.

The circuit interrupting means shown in Figs. 10 and 11 is intended to be utilized in the same manner as the circuit interrupting means M^2 shown in Figs. 8 and 9, and when utilized in this manner, the operation of the apparatus as a whole, will be readily understood from the foregoing without describing it in detail.

Although we have herein shown and described only four forms of apparatus embodying our invention, it is understood that various changes and modifications may be made therein within the scope of the appended claims without departing from the spirit and scope of our invention.

Having thus described our invention, what we claim is:

1. Apparatus for indicating the speed of a movable body comprising a first member adapted to be oscillated at a frequency which varies with the speed of the body, an inertia member pivotally mounted on said first member, a fixed contact member carried by said first member, a second contact member carried by said inertia member, a spring carried by said first member and arranged to bias said inertia member to a position in which said second contact member engages said fixed contact member, and an electroresponsive indicating device controlled by the contact formed by said second contact member and said fixed contact member.

2. Apparatus for indicating the speed of a movable body comprising a first member adapted to be oscillated at a frequency which varies with the speed of the body, an inertia member pivotally mounted on said first member, a fixed contact member carried by said first member, a second contact member carried by said inertia member and adapted

to cooperate with said fixed contact member, a spring secured to said first member and to said inertia member and arranged to bias said inertia member to the position in which
 5 the contact formed by said fixed contact member and said second contact member is open, and an electroresponsive indicating device controlled by the contact formed by said fixed contact member and said second contact
 10 member.

3. Apparatus for indicating the speed of a movable body comprising a first member adapted to be oscillated at a frequency which varies with the speed of the body, an inertia
 15 member mounted to oscillate about the same axis as said first member, a fixed contact member carried by said first member, a second contact member carried by said inertia member, a spring carried by said first member and arranged to bias said inertia member to a position in which said second contact member engages said fixed contact member, and an electroresponsive indicating device controlled by the contact formed by said second contact member and said fixed contact
 20 member.
 25

4. Apparatus for indicating the speed of a movable body comprising a first member adapted to be oscillated at a frequency which
 30 varies with the speed of the body, a pivoted inertia member, a fixed contact member carried by said first member, a second contact member carried by said inertia member, a spring carried by said first member and arranged to bias said inertia member to a position in which said second contact member engages said fixed contact member, and an electrical circuit controlled by the contact formed by said second contact member and said fixed
 35 contact member; said circuit including an asymmetric unit connected in multiple with a slow-acting relay and a reactance in series.

5. Apparatus for indicating the speed of a movable body comprising a first member
 40 which is adapted to be oscillated at a frequency which varies with the speed of the body, a plurality of inertia members pivotally mounted on said first member, a plurality of fixed contact members carried by said first member, a plurality of other contact members one attached to each inertia member and each adapted to cooperate with a different one of said fixed contact members, a plurality of springs carried by said first member and each arranged to bias a different one of said inertia members to the position in which the contact member carried by the associated inertia member engages the associated fixed contact, said springs being adjusted to exert
 45 different biasing forces, and a plurality of electroresponsive indicating devices one controlled by the contact formed by each said other contact member and the associated fixed contact member.

6. Apparatus for indicating the speed of

a movable body comprising a first member which is adapted to be oscillated at a frequency which varies with the speed of the body, a plurality of inertia members mounted to oscillate about the same axis as said first member, a plurality of fixed contact members carried by said first member, a plurality of other contact members one attached to each inertia member and each adapted to cooperate with a different one of said fixed contact members, a plurality of springs carried by said first member and each arranged to bias a different one of said inertia members to the position in which the contact member carried by the associated inertia member engages the associated fixed contact, said springs being adjusted to exert different biasing forces, and a plurality of electroresponsive indicating devices one controlled by the contact formed by each said other contact member and the associated fixed contact member.

7. In speed responsive apparatus for electrically indicating the speed of a movable body by periodically interrupting the supply of current to an inductive electrical circuit including an electroresponsive indicating device which is selectively responsive to the average value of the current in its winding, in combination, circuit interrupting means comprising a first member oscillated at a speed which varies with the speed of the body, an inertia member pivotally mounted on said first member, a fixed contact member secured to said first member, a second contact member carried by said inertia member, and a spring carried by said first member and arranged to bias said inertia member to a position in which said second contact member engages said fixed contact member.

8. In speed responsive apparatus for electrically indicating the speed of a movable body by periodically interrupting the supply of current to an inductive electrical circuit including an electroresponsive indicating device which is selectively responsive to the average value of the current in its winding, in combination, circuit interrupting means comprising a first member oscillated at a speed which varies with the speed of the body, an inertia member pivotally mounted to oscillate about the same axis as said first member, a fixed contact member secured to said first member, a second contact member carried by said inertia member, and a spring carried by said first member and arranged to bias said inertia member to a position in which said second contact member engages said fixed contact member.

9. In speed responsive apparatus for electrically indicating the speed of a movable body by periodically interrupting the supply of current to an inductive electrical circuit including an electroresponsive indicating device which is selectively responsive to the

- average value of the current in its winding, in combination, circuit interrupting means comprising a first member oscillated at a speed which varies with the speed of the body, a plurality of inertia members pivotally mounted to oscillate about the same axis as said first member, a plurality of fixed contact members carried by said first member, a plurality of other contact members one carried by each inertia member and each adapted to cooperate with a different one of said fixed contact members, and a plurality of springs carried by said first member and each arranged to bias a different one of said inertia members to the position in which the contact member carried by such inertia member engages the associated fixed contact member, said springs being adjusted to exert different biasing forces.
10. In speed responsive apparatus for electrically indicating the speed of a movable body by periodically interrupting the supply of current to an inductive electrical circuit including an electroresponsive indicating device which is selectively responsive to the average value of the current in its winding, in combination, circuit interrupting means comprising a first member oscillated at a speed which varies with the speed of the body, an inertia member pivotally mounted to oscillate about the same axis as said first member, a fixed contact member carried by said first member, a leaf spring secured to said inertia member and provided at one end with a contact tip which cooperates with said fixed contact member, and means carried by said first contact member and cooperating with the other end of said leaf spring in such manner that said spring biases said member to the position in which said contact tip engages said fixed contact member.
11. In speed responsive apparatus for electrically indicating the speed of a movable body by periodically interrupting the supply of current to an inductive electrical circuit including an electroresponsive indicating device which is selectively responsive to the average value of the current in its winding, in combination, circuit interrupting means comprising a first member oscillated at a speed which varies with the speed of the body, an inertia member pivotally mounted to oscillate about the same axis as said first member, a fixed contact member carried by said first member, a leaf spring secured to said inertia member and provided at one end with a contact tip which cooperates with said fixed contact member, and a plug adjustably screwed through said first member and provided at its inner end with an insulating insert which cooperates with the other end of said leaf spring in such manner that said spring biases said member to the position in which said contact tip engages said fixed contact member.
12. Apparatus for indicating the speed of a movable body comprising a first member adapted to be oscillated at a frequency which varies with the speed of the body, a pivoted inertia member, a fixed contact member carried by said first member, a second contact member carried by said inertia member, a spring carried by said first member and arranged to bias said inertia member to a position in which said second contact member engages said fixed contact member, means for adjusting the biasing force exerted by said spring, and an electroresponsive indicating device controlled by the contact formed by said second contact member and said fixed contact member.
13. Apparatus for indicating the speed of a movable body comprising a first member adapted to be oscillated at a frequency which varies with the speed of the body, a pivoted inertia member, a fixed contact member carried by said first member, a second contact member carried by said inertia member, a spring carried by said first member and arranged to bias said inertia member to a position in which said second contact member engages said fixed contact member, means for adjusting the biasing force exerted by said spring, the parts being so proportioned that at all frequencies of oscillations of said first member above a predetermined frequency the inertia of said inertia member will stress said spring once during each oscillation sufficiently to open the contact formed by said second contact member and said fixed contact member for an interval of time which increases as the speed of the body increases, and an electroresponsive indicating device controlled by the contact formed by said second contact member and said fixed contact member.
14. Apparatus for indicating the speed of a movable body comprising a first member adapted to be oscillated at a frequency which varies with the speed of the body, a pivoted inertia member, a fixed contact member carried by said first member, a second contact member carried by said inertia member, a spring carried by said first member and arranged to bias said inertia member to a position in which said second contact member engages said fixed contact member, means for adjusting the biasing force exerted by said spring, the parts being so proportioned that at all frequencies of oscillation of said first member above a predetermined frequency the inertia of said inertia member will stress said spring once during each oscillation sufficiently to open the contact formed by said second contact member and said fixed contact member for an interval of time which increases as the speed of the body increases, and an electroresponsive indicating device controlled by the contact formed by said second contact member and said fixed contact member.

contact member and selectively responsive to the proportion of the open time of said contact to a fixed interval of time.

15. In speed responsive apparatus, the combination of a first member operated through successive cycles at different frequencies, an inertia member pivoted on the first member and sustaining from the movement of the first member a secondary motion, and means connecting the inertia member with the first member and constantly urging the two members to a definite relative position with a force derived partly from the movements of the members and tending to produce a critical condition corresponding to a definite frequency of the first member beyond which a cyclic change in the relative positions of the two members takes place.

16. In speed responsive apparatus, the combination of a first member operated through successive cycles at different frequencies, an inertia member pivoted on the first member and sustaining from the movement of the first member a secondary motion, a first contact member carried by the first member, a second contact member carried by the inertia member, and means connecting the inertia member with the first member and constantly urging the inertia member to the relative position with respect to the first member in which said second contact member engages said first contact member with a force derived partly from the movements of the members and tending to produce a critical condition corresponding to a definite frequency of the first member beyond which a cyclic separation of the two contact members takes place.

17. In speed responsive apparatus, the combination of a first member operated through successive cycles at different frequencies, an inertia member pivoted on the first member and sustaining from the movement of the first member a secondary motion, a first contact member carried by the first member, a second contact member carried by the inertia member, and means connecting the inertia member with the first member and constantly urging the inertia member to the relative position with respect to the first member in which said second contact member engages said first contact member with a force derived partly from the movements of the members and tending to produce a critical condition corresponding to a definite frequency of the first member beyond which a cyclic separation of the two contact members take place, the duration of which separation varies rapidly with slight changes in frequency beyond the critical frequency.

In testimony whereof we affix our signatures.

PER UTNE.
RALPH K. CROOKS.
